C. J. DIEBOLD

WHISTLING BALL

Filed July 3, 1926

Inventor

C. J. Diebold

By

C. J. Diebold

UNITED STATES PATENT OFFICE.

CHARLES J. DIEBOLD, OF WINNIPEG, MANITOBA, CANADA.

WHISTLING BALL.

Application filed July 3, 1926. Serial No. 120,406.

The invention relates to improvements in whistling balls and an object of the invention is to provide a non-bouncing ball having a whistle therein which will give a musical sound on the projection and recoil of the ball, the ball being suspended by an elastic string.

A further object is to construct the device in a simple, durable and inexpensive manner and such that the parts can be readily assembled, such permitting of the marketing of the ball at a reasonable price.

A further object is to provide a whistling ball wherein the whistle is operated by a bellows contained within the ball and wherein the bellows is held collapsed by the action of an internal spring and wherein the spring normally counterbalances the weight of the ball and other parts suspended by the string, such arrangement rendering the device extremely sensitive.

A further object of the invention is to provide a flexible bellows and an operating string attached thereto and passing out of a comparatively large hole in the ball, such permitting of the free escape of air from the interior of the ball and also of the free manipulation of the bellows and the string when the ball is in motion.

With the above more important objects in view, the invention consists essentially in the arrangement and construction of parts hereinafter more particularly described, reference being had to the accompanying drawing, in which:—

Fig. 1 is a vertical sectional view centrally through the ball and contained parts.

Fig. 2 is a horizontal sectional view at 2—2' Figure 1.

Fig. 3 is a horizontal sectional view at 3—3' Figure 1.

Fig. 4 is a perspective view of the whistle.

In the drawing like characters of reference indicate corresponding parts in the several figures.

The ball 1 is not intended to be a bouncing ball and accordingly it is made from a light non-resilient material such as wood pulp and is formed from an upper section 2 and a lower section 3, these being suitably cemented together at the joint 4. The ball is provided with diametrically opposing openings or holes 5 and 6 and the upper hole 5 is protected by an applied ferrule 7.

The whistle 8 which I employ is of well

known design being cylindrical in form and constructed from two telescoping sections which fit tightly together. The holes in the whistle are indicated at 9 and 10 and the diameter of the whistle is somewhat greater than the diameter of the lower hole 6 of the ball.

A lower annular disc 11 is provided and the whistle is pushed tightly into the opening of the disc. The under face of the disc is curved to conform to the shape of the ball. An upper disc 12 is also supplied, the diameter of which is the same as the outer diameter of the lower disc. I find it also economical to make the discs from wood pulp. A bellows covering 13 connects the discs, being passed therearound. The bellows covering is formed from a rectangular strip of rubberized cheese cloth and the opposite edges of the strip are suitably cemented together to form a cylinder and then the ends of the cylinder are passed around the discs and suitably cemented thereto.

Within the bellows formed by the discs and covering, I locate a comparatively fine steel wire coiled spring 14 which has the lower end soldered to the whistle and the other end suitably attached to the upper disc as by passing the end of the wire therethrough and subsequently bending it. A wire staple 15 is attached centrally to the upper disc and to the wire staple, I secure the inner end of a length of elastic cord or string 16 which passes out through the opening 5 and terminates in a finger ring 17.

After the spring has been secured to the whistle and the bellows has been built up, I firmly cement the lower annular disc 11 to the lower half of the ball and with the whistle holes axially aligned with the centre of the opening 6, it being understood that the upper half of the ball is at such time removed. Subsequently the string is passed through the hole 5 and the upper half of the ball is cemented to the lower half.

When the whistling ball has been completed and the same is idly suspended by the string, the bellows is in what might be termed the collapsed or contracted position as the spring is designed to withstand the weight of the ball and other parts with the bellows collapsed. In other words, the strength of the spring is such that it just nicely counterbalances the weight of the ball and other suspended parts and accord-

ingly the whistling ball is extremely sensitive, that is to say, it takes very little motion of the ball to start it whistling.

When the ball is projected, air is drawn into the bellows and in passing through the openings of the whistle causes a whistling sound. When the ball recoils, the spring closes the bellows and passes air through the whistle in the opposite direction to cause a further whistling sound.

I have found that by making the opening 5 comparatively large in respect to the size of the string, I obtain a much better whistling effect than if said opening were small as apparently, it is desirable that the air be free to enter and escape quickly when the bellows is expanding and contracting.

By making the bellows flexible and the opening 5 comparatively large and suspending the ball from the bellows, the bellows and ball are given free movement and there is no possibility of any of the parts binding or being injured in any way.

I am aware that whistles have been heretofore used in connection with balls but in such the structure is so complicated and costly that the device cannot be marketed at a reasonable price and further the working parts are of such a rigid nature that freeness of movement is not permitted and the device is not sensitive and further there is every possibility of the working parts getting out of order.

What I claim as my invention is:—

1. In combination, a hollow ball having

opposing end openings therein, an annular disc surrounding one of the openings and secured to the ball, a whistle carried by the disc and covering said latter opening, an upper disc, a flexible bellows forming material connecting the discs, a spring within the bellows and having the lower end secured to the whistle and the upper end attached to the upper disc and a string attached centrally to the upper disc and passing out through the other end hole in the ball, the said spring maintaining the bellows in a collapsed position upon the ball being suspended by the string.

2. In combination, a hollow ball formed from upper and lower sections and having opposing openings in the upper and lower ends thereof, an annular disc within and secured to the lower end of the ball and surrounding the lower opening, a whistle inserted within the disc and covering the latter opening, an upper disc opposing the former annular disc, a flexible bellows forming material connecting the discs, an elastic string connected centrally to the upper disc and passing outwardly through the upper end opening in the ball, said latter end opening being considerably larger than the string and a spring within the bellows and having one end secured to the whistle and the other to the upper disc, said spring being designed to suspend the weight of the ball whilst maintaining the bellows normally in a collapsed position.

CHARLES J. DIEBOLD.
